DESIGN FOR A MAT

Hunter McKay, Cambridge, Mass., assignor to Boston Woven Hose and Rubber Company,
Cambridge, Mass., a corporation of Massachu-
sets

Application November 16, 1934, Serial No. 54,038

Term of patent 7 years

To all whom it may concern:

Be it known that I, Hunter McKay, a citizen of the United States, residing at Cambridge, in the county of Middlesex and Commonwealth of Massachusetts, have invented a new, original, and ornamental Design for a Mat, of which the following is a specification, reference being had to the accompanying drawing, forming a part thereof, in which

The figure is a view in perspective of a mat showing my new design.

I claim:

The ornamental design for a mat substantially as shown.

In testimony whereof, I have affixed my signature hereto.

HUNTER MCKAY.
